UNITED STATES PATENT OFFICE.

EDGAR A. SOLOMON, OF PITTSBURGH, PENNSYLVANIA.

BEDSTEAD.

1,278,050.

Specification of Letters Patent.

Patented Sept. 3, 1918.

Application filed June 30, 1917. Serial No. 177,961.

To all whom it may concern:

Be it known that I, EDGAR A. SOLOMON, a citizen of the United States, residing at Pittsburgh, in the county of Allegheny and 5 State of Pennsylvania, have invented certain new and useful Improvements in Bedsteads, of which the following is a specification.

My invention refers to improvements in 10 bed springs, and particularly to the mattress supporting frame. It has for its object to provide a strong, rigid and simple frame having means for holding the terminal spring attaching members in operative position, and providing in such members for 15 positive engagement against the edges of the mattress, whereby to retain it in position, as hereinafter described.

In the drawings showing one preferred 20 embodiment of the invention:

Figure 1 is a perspective view of the frame with a partly turned mattress in position.

Fig. 2 is a perspective detail view of one 25 of the corner brackets.

Fig. 3 is a partial view of one of the end-most angle bars.

Fig. 4 is a detail plan view of the corner 30 bracket with the connecting angle bar in position, partly broken away.

Fig. 5 is a sectional detail view, indicated by the line V, V, of Fig. 4.

In the drawings 2, 2, are the usual side bars of the mattress frame, of pipe or other 35 suitable constructions, the ends of which are inserted in sockets 3 of the corner brackets. These corner brackets are preferably made as castings of right and left form, and comprise the principal corner portions of the 40 frame, and the foundation structure for the mattress supports. They rest upon the main bedstead framework by lateral shoes 5 and extend upwardly by leg portions 6, 7, connected at the top by a supporting cross bar 45 8 as shown. Portions 6, 7, are offset, lengthwise of the frame in opposite directions at each end to insure ample length for the mattress, thereby extending somewhat beyond the limitations of a standard size bed 50 spring frame, so that the available length of the spring bottom is not reduced by the width of the angle bars 9. Said bars ex-

tend across each end, connecting the corner brackets, and being secured to the plates 8 thereof by bolts passing through apertures 55 10 and a stud 11 which fits into a receiving pocket 12 at each end portion of the angle bar. The outer bracket leg 7 is extended above the plate 8 as shown at 13 forming a retaining abutment for the upright flange 60 of the angle bar 9 and leg 7 is also extended edgewise inwardly as indicated at 14, providing a similar abutment for the lower horizontal flange of the angle bar. By this means the cross bar is positively braced and 65 covered at each end, and a retaining pocket is provided for the edges of the mattress A by the inwardly extending portions 13.

Stud 11 and its socket 12 are shown as of diamond form, but any other suitable shape 70 may be used, the top of the stud being preferably flush with the upper face of the angle bar, so that it is thus fixedly held in position and assisted in the process of erection, independent of the bolts 10. The inner 75 edges of the angle bars 9 are provided with a series of holes 15 for connecting the terminals of the spring web mattress support a as will be readily understood. Heretofore such cross bars have been made of angle 80 shape, but in a reverse position, and it will be seen that by my invention I utilize the angle bar, in connection with the corner brackets, to provide an efficient mattress support and spring connection having the 85 advantages noted, with a minimum of material, at low cost, and a continuous efficiency in use. One particular advantage of the upright retaining flange of the cross bar is that it provides a positive limiting 90 stop for the mattress in turning or manipulating it, with either a single or double mattress.

The invention may be changed or varied 95 in size, proportions, detail construction or otherwise by the skilled mechanic, but all such changes are to be understood as within the scope of the following claim.

What I claim is:

The combination with an angle shaped 100 end bar of a mattress supporting frame having its one side extending upwardly and its other side extending inwardly, of a corner bracket comprising a tubular base portion

forming a side bar socket, upwardly extending side arms, a connecting flat top bar having an upwardly extending stud adapted to be engaged within an aperture in said end 5 bar, and an outer L-shaped retaining abutment formed integral with one of said side arms and extending upwardly from said

top bar and abutting the end of said end bar, said retaining abutment extending beyond the end of said end bearing to prevent lateral movement of a mattress.

In testimony whereof I hereunto affix my signature.

EDGAR A. SOLOMON.
